United States Patent Office

Des. 220,753
Patented May 18, 1971

220,753

CONTAINER END

Arthur P. Zundel, 5959 S. Cicero Ave., Cary, Ill. 60638

Filed Jan. 26, 1970, Ser. No. 21,080

Term of patent 14 years

Int. Cl. D9—99

U.S. Cl. D9—253

FIG.2

FIG.1

FIG.3

FIG.4

FIG.5

FIG. 1 is a perspective view of a container end, showing my new design;

FIG. 2 is a top plan view;

FIG. 3 is a side elevational view;

FIG. 4 is a bottom plan view; and

FIG. 5 is an enlarged scale sectional view.

I claim:

The ornamental design for a container end, as shown.
